US0D1023465S

(12) **United States Design Patent** (10) **Patent No.:** **US D1,023,465 S**
(45) **Date of Patent:** **** Apr. 16, 2024**

(54) **NAIL POLISHER**

(71) Applicant: **Xin Wang**, Guang'an (CN)

(72) Inventor: **Chunmei Guo**, Leshan (CN)

(73) Assignee: **Xin Wang**, Guang'an (CN)

(**) Term: **15 Years**

(21) Appl. No.: **29/841,907**

(22) Filed: **Jun. 9, 2022**

(30) **Foreign Application Priority Data**

May 24, 2022 (CN) 202230310262.3

(51) **LOC (14) Cl.** **28-03**

(52) **U.S. Cl.** **D28/58**
USPC **D28/58**

(58) **Field of Classification Search**

USPC D28/58, 59; 132/73, 73.5, 73.6
CPC A45D 29/05; A45D 29/11; A45D 29/12;
A45D 29/14; A45D 29/18

See application file for complete search history.

(57) **CLAIM**

The ornamental design for a nail polisher, as shown and described.

DESCRIPTION

FIG. 1 is a perspective view of a nail polisher, showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view thereof;

FIG. 7 is an enlarged bottom plan view thereof; and,

FIG. 8 is a front view of the design in an open status.

The broken lines shown in the drawings of the nail polisher are for the purpose of illustrating portions of the article that form no part of the claimed design.

1 Claim, 8 Drawing Sheets
